APPARATUS FOR REMOVING METAL

James L. Anderson, Closter, N. J., assignor to Air Reduction Company, Incorporated, New York, N. Y., a corporation of New York

Application April 18, 1935, Serial No. 17,070

15 Claims. (Cl. 266—23)

This invention relates to apparatus for removing metal from metal bodies, and especially to apparatus for surfacing steel billets.

As they come from the blooming mill, steel billets have a coating of oxide on their surfaces and have various other imperfections, such as pockmarks, laps, surface cracks, and mill scale adhering to or rolled into the surface. In order to obtain a perfect surface on articles rolled from the billet, metal is removed from the faces of the billet to the depth of these imperfections by directing a stream of oxidizing gas against the metal.

It is an object of this invention to reduce the time and cost of billet surfacing by providing improved apparatus which performs the operation quickly and with less oxygen and labor than formerly required. In accordance with one feature of the invention, torches are connected with a carriage which runs on a track between parallel billet tables. The torches are directed against the surface of a billet on one table while the carriage moves along the track in a forward direction, and the torches are then shifted into position to direct jets against a billet on the other table while the carriage travels in the opposite direction. The billet on the first table is turned or replaced while the torches are surfacing the billet on the second table.

The invention provides a novel construction and combination of elements for positioning the torches over the billet conveniently and quickly and for regulating from a distance the spacing of the torches from the billet surface.

Another object of the invention is to provide improved torch-holding means for simultaneously shifting a plurality of torches into positions for surfacing either plane, twisted and/or transversely curved billet faces.

Other objects, features and advantages of the invention will appear or be pointed out as the specification proceeds.

In the accompanying drawings, forming part hereof:

Fig. 1 is a top plan view of billet surfacing apparatus embodying this invention.

Fig. 2 is an enlarged side elevation of the billet surfacing machine shown in Fig. 1.

Fig. 3 is an enlarged end view of the apparatus shown in Fig. 1, looking toward the left.

Fig. 4 is an enlarged front view of the torches and means for adjusting the torches to operate over plane, concave or convex surfaces.

Figs. 5—7 are sectional views taken on the lines 5—5, 6—6, and 7—7, respectively, in Fig. 4.

A base or carriage 10 has wheels 11 which run on a track comprising rails 12 fastened to the ties 13. Abutments 15 at the ends of the rails serve as bumpers to prevent the carriage from running beyond the ends of the track. Billet 5 tables 17 and 18 extend along opposite sides of the track, substantially parallel with the track, and support billets 19 in end-to-end relation, as shown in Fig. 1. Steel brushes 20 attached to the carriage sweep the tracks ahead of the wheels. 10

An arm 21 is supported from the carriage 10 by a support 22. The arm 21 extends beyond the side of the carriage and holds a frame 24 over the billets. Torches 25 carried by the frame 24 surface the billets on the table 18 as the carriage 15 travels along the rails toward the right in Fig. 1. The support 22 can be rotated on a bearing 26 about a vertical axis which is substantially midway between the billet tables 17 and 18 so that rotation of the support swings the torches which 20 were surfacing the billets on the table 18 into position to surface the billets on the table 17. A lock or clamping screw 28 is used to prevent the support 22 from rotating when the carriage 25 is traveling.

Billets are put on the table 18 in end-to-end relation as shown in Fig. 1. The torches are positioned over the end billet, by mechanism which will be described, and the carriage is driven to the right while the torches surface the first billet. 30 The supply of oxygen to the torches is cut off by the attendant when the torches reach the end of the first billet, and the carriage is stopped with the torches in position to preheat the end of the next billet. As soon as the metal is heated sufficiently to start the surfacing operation, the oxygen jets are again turned on and the movement of the carriage continued toward the right. While the machine is operating to surface billets on the table 18, other billets are placed on the 40 table 17.

When the carriage 10 reaches its limit of travel to the right, the support 22 is rotated to bring the torches into position to operate over the billets on the table 17. While the carriage travels 45 to the left along the track and moves the torches across the billets on the table 17, the surfaced billets on the other table are turned to expose an unsurfaced side, or removed and replaced with new billets. The machine can, therefore, operate 50 continuously with no interruption for the handling of billets.

The carriage is driven by an electric motor 30 through reduction gearing 31, and sprocket chains 33 and 34. The supply of power to the motor 55

is controlled by switches operated by push-buttons 36 located on the support 22. The speed of the motor is controlled by a rheostat 37. The motor is equipped with magnetic braking which stops the motor quickly when the power is shut off. Thus both the starting and stopping of the carriage are in immediate response to the operation of the push-buttons 36, and it is possible for the attendant to accurately position the torches at the end of a billet in position for preheating.

The attendant sits on a seat 40 supported by a bracket 41 which connects with the support 22 so that the seat moves with the support when the torches are swung from one side of the carriage to the other. This movement of the seat keeps the attendant in the same relative position with respect to the torches so that he can watch the billet surfacing operation and make adjustments if it becomes necessary. The connection of the seat to the support 22 enables the attendant to swing the support by walking around the bearing 26 while sitting on the seat 40.

Figs. 2 and 3 show the construction of the arm 21, support 22, and frame 24. The support 22 includes a cylindrical lower end which fits into a pedestal 44. This pedestal is a rigid part of the carriage and the upper end of the pedestal is the bearing 26. The support 22 has a shoulder against the bearing 26, and a joint 46 allowing movement of the upper portion of the support to obtain a true horizontal position for the arm 21. After obtaining the horizontal adjustment of the arm 21, the joint 46 is locked by a clamping screw 47.

The upper portion of the support 22 has vertically spaced, grooved tracks 49 and 50. The upper and lower edges of the arm 21 slide in these grooved tracks to obtain a horizontal movement of the arm transversely of the carriage. A rack 51 on the arm 21 meshes with a pinion 52 secured on a shaft 53 which turns in bearings in the support 22 and has a hand-wheel 54 within convenient reach of the attendant for moving the arm 21 in the grooved tracks 49 and 50.

A worm wheel 56 on the end of the shaft 53 remote from the wheel 54 is connected to the shaft 53 by a clutch 57 which is engaged and disengaged by operating a hand-wheel 58. The shaft 53 is hollow and the hand-wheel 58 is connected with the clutch by a rod 60 extending through the shaft 53. A worm 61 engages the worm wheel 56 and is fixed on a vertical shaft 62. This shaft turns in bearings in the support 22 and has a hand-wheel 63 at its upper end.

When the clutch 57 is not engaged, the shaft 53 turns freely in the worm wheel 56, but when the clutch is engaged the shaft 62 and worm 61 must be rotated in order to turn the shaft 53. The arm 21 is moved to the approximately correct position by turning the hand-wheel 54, and final exact adjustment is obtained with the hand-wheel 63 which moves the arm 21 through very small distances in proportion to the movement of the hand-wheel.

The arm 21 has bearings 66 supporting a shaft 67 extending from one end of the arm 21 to a hand-wheel 68. The hand-wheel 68 is secured to a short shaft 70 with a worm 71 which engages a worm wheel 72 fastened to the shaft 67. The short shaft 70 turns in bearings in the arm 21.

The frame 24 comprises a slide 73 movable vertically in guides 74 on the end of the arm 21. A rack 75 on the slide 73 meshes with a pinion 76 on the shaft 67. The pinion 76 turns with the shaft 67 to raise or lower the slide 73 whenever

the hand-wheel 68 is rotated. The worm 71 has a slow pitch so that the gearing connection between the hand-wheel 68 and shaft 67 is irreversible and holds the slide 73 in any set position.

A lever 78 is connected with the lower end of the slide 73 by a pivot 79 which serves as the fulcrum of the lever. A gear sector 80 at the upper end of the lever 78 engages a gear 82. This gear turns on a pin 83 fixed to the slide 73. A handle 84 connected to the gear 82 is used to turn the gear and adjust the position of the lever 78 so that the tips of the torches supported from the lever are in a line parallel to the surface of the billet or along a curve concentric with the transverse curve of a concave or convex billet face. If the billet is twisted, the handle 84 can be moved to progressively change the position of the torches in accordance with the twist of the billet. In addition to the rocking of the torches by means of the handle 84, it is necessary to effect a slight raising or lowering of the torches by operating the hand-wheel 68 and/or a shifting of the torch-carrying frame transversely by operating the hand-wheel 63.

A yoke 86 is fastened to the lower end of the lever 78 and has pivot connections 87 with side members 88 of the torch-supporting frame. The side members 88 are connected by lower and upper cross members 89 and 90.

The torches 25 are clamped in torch holders 89 carried by the cross member 89. Each torch holder comprises upper and lower split clamp blocks 91 connected with a short T section 92 on the other side of the cross member 89 by screws 93 which extend through the cross member. The screws 93 of all except the end torch holders extend through vertical slots 94 in the cross member 89. Each of the blocks 91 has a projection of reduced width on its front side fitting the slot 94 but somewhat shorter than the slot in a vertical direction so that the block has a limited vertical movement in the slot. The blocks 91 of adjacent torch holders are staggered in order to place the torch holders closer together.

With the torch holders in the positions shown in Figs. 3 and 4, the torches 25 are clamped in the holders in such relation that the torch tips extend in a straight line.

The torch tips direct streams of oxidizing gas at an acute angle to the surface of the billet. The streams are preferably, though not necessarily, also directed at a lateral inclination to the direction of movement of the torches, as disclosed in my copending application Serial No. 13,983, filed March 30, 1935.

The frame 24 has a limited angular movement about the pivot connections 87 to change the inclination of the torch tips with respect to the surface of the billet. Links 96 connect the frame 24 with cranks 97 on the opposite ends of a shaft 98. The shaft 98 extends through bearings 99 on the lever 78, and has a handle 100 with a pawl 101 (Fig. 3) which engages the teeth of a gear segment 102 fastened to the lever 78. The maximum movement of the handle 100 tips the frame 24 through the angle indicated in Fig. 2 by the full line and the dotted line positions of the side member 88. The pawl 101 will hold the frame in intermediate positions.

The torches 25 connect with gas manifolds 104 extending along the cross member 90 of the torch-supporting frame 24. Gas is supplied to the manifolds from conduits 105 (Fig. 1) supported on the arm 21 by brackets 106. The conduits 105 are connected with the manifolds 104 by flexible hose 75.

108 which permit vertical movement of the torch-supporting frame 24 as well as tipping of the frame to change the inclination of the tips with respect to the billet. The gas supply is controlled 5 by valves 110 located within convenient reach of the attendant.

The torch tips can be shifted into concave and convex arcs of various curvature for surfacing concave or convex billet surfaces. The positions 10 of the end torch holders on the cross member 89 (Fig. 4) are fixed. The center torch holder has a pivot connection 115 with a lever 116. The fulcrum of the lever 116 is a pivot connection 117 between the lever and the cross member 89.

15 The upper end of the lever 116 has a projection 119 (Fig. 7) which engages notches in a notched plate 120 fastened to one of the side members 88. The lever 116 is held against the notched plate 120 by a spring 121 which bears 20 against a stirrup 122 fastened to the side member 88. The lever 116 extends beyond the side member 88 to provide a handle within convenient reach of the attendant.

A stiff leaf spring 124 (Fig. 4) extends through 25 all of the T sections 92 of the torch holders. The ends of this spring have no vertical movement with respect to the cross member 89 because the end torch holders are fixed on this cross member. The center of the spring 124 30 moves up and down with the center torch holder as the lever 116 is shifted to raise and lower the pivot connection 115. This pivot connection 115 is loose enough to allow vertical movement of the torch holder while the lever moves about a center.

35 Downward movement of the center torch holder bends the leaf spring 124 into a concave arc, and raising the center torch above the straight-line position of Fig. 4 bends the leaf spring into a convex arc. Such bending of the spring moves 40 the torch holders and causes the torch tips to take positions along a line having substantially the same curvature as the spring 124. This curvature can be changed by moving the handle 116 into different notches of the plate 120. Other 45 means for shifting the torch tips into convex and concave relation may be employed.

The machine of this invention is adapted for removing the surface not only from billets but from metal bodies of various kinds. In the preferred embodiment of the invention the torches are moved while the billets remain stationary, but it will be understood that the necessary relative movement can be obtained by moving the billets or other metal bodies to be surfaced past 50 stationary torches, or by moving the billets and torches simultaneously in opposite directions. In practice it has proved somewhat easier to move the torches and maintain a constant spacing of the torches from the surface of the metal body than it is to move the bodies and maintain the spacing constant. Other changes can be made, and some features of the invention may be used 55 without others, without departing from the invention as defined in the claims.

60 I claim:

65 1. Apparatus for surfacing metal bodies comprising a base, means for supporting a row of bodies to be surfaced, means for causing relative movement of the base and said bodies in the direction that the row of bodies extends, an arm carried by the base, and means on the arm for supporting a plurality of torches in position to surface the bodies successively during said relative movement.

70 2. Billet surfacing apparatus comprising two

spaced, parallel billet tables, a track between said tables and extending parallel to the tables, a carriage on the track, means for driving the carriage in either direction along the track, a support with means for holding billet surfacing 5 torches, and means connecting the support with the carriage for rotary movement to swing the torches from a position over one billet table to a corresponding position over the other billet table so that the torches can surface a billet on one 10 table while the carriage travels in one direction along the track and surface a billet on the other table while the carriage travels along the track in the opposite direction.

3. Apparatus for surfacing metal bodies comprising a base, means for supporting bodies along both sides of the base, means for moving the base parallel to the bodies, an arm with holders for supporting a plurality of torches in position to surface a body on one side of the base during the 15 movement of the base in one direction, and a swivel connection between the arm and base on which the arm is rotatable to move the torches into position to surface a body on the other side of the base while the base travels in the opposite 20 direction.

4. A billet surfacing machine comprising a carriage, a torch-supporting arm for holding torches in position to surface a billet extending along a side of the carriage, a swivel connection between 30 the arm and carriage on which the arm swings to move the torches into position to surface billets on either side of the machine, a seat for an attendant, and connections for causing the seat to swing with the arm to maintain the seat in the 35 same position relative to the torches when operating on a billet along either side of the carriage.

5. A machine for surfacing metal bodies including in combination a carriage, an arm connected to and extending transversely of the carriage, a frame carried by the arm adjacent one end of the arm, torch holders on the frame for supporting torches, means for causing the arm to move transversely of the carriage to position 40 said frame over a body to be surfaced, and means 45 for raising and lowering the frame to control the spacing of the torches from the surface of the body.

6. A machine for surfacing metal bodies comprising a base, a transversely extending arm, a 50 support for said arm connected with the base, a frame depending from one end of the arm beyond the base, holders on the frame for supporting torches in position to surface a body alongside the base, means on the arm support for causing the arm to move transversely to locate the torches at the desired spacing from the side of the base, and other means on the arm support for raising and lowering the frame to control the 55 spacing of the torches from the body to be surfaced.

7. A machine for surfacing metal bodies comprising a base, an upright post connected with the base and rotatable about a vertical axis, a horizontal arm at the upper end of the post with 60 one end of the arm extending beyond the side of the base, a frame depending from the end of the arm, torch holders on the frame for supporting a row of torches in position to surface a metal body alongside the base, the arm and frame being 65 rotatable as a unit with the post to locate the torches on either side of the base and movable as a unit transversely of the base to locate the torches over bodies at different distances from the base, and means for raising and lowering the 70 75

- frame with respect to the arm to regulate the spacing of the torches from said bodies.
8. A machine for surfacing metal bodies comprising a base, an arm extending transversely beyond one side of the base, a support for said arm, means connecting said support to the base including a bearing on which the support is movable to rotate the arm into a position in which it extends beyond the other side of the base, a frame depending from one end of the arm beyond the base, holders on the frame for supporting torches in position to surface a body alongside the base, means on the arm support for causing the arm to move transversely to locate the torches at the desired spacing from the side of the base, and other means on the arm support for raising and lowering the frame to control the spacing of the torches from the body to be surfaced.
- 20 9. A machine for surfacing metal bodies including a carriage, an arm extending transversely beyond one side of the carriage, a support for the arm connected with the carriage, and rotatable about a vertical axis to move the arm into position where it extends beyond the other side of the carriage, brackets on the arm support holding gas conduits, a frame depending from the end of the arm which extends beyond the side of the carriage, torch holders at the lower end of the frame, means for moving the arm and frame horizontally as a unit with respect to the support to change the spacing of the torches from the side of the carriage, means for moving the frame vertically with respect to the arm to space the torches from a body to be surfaced, and flexible hose for supplying gas from the conduits on said support to the torches on the frame.
10. In a machine for surfacing metal bodies, a base, means for causing relative movement of the base and the bodies to be surfaced, a support on the base, an arm extending from the support, a torch-holder frame carried by the arm and located over the bodies, and manually operated means including irreversible gearing for moving the torch-holder frame vertically to adjust its spacing from the bodies, said gearing comprising a slow pitch worm of such a nature that it is not operable by the load on the frame and said frame remains in any set position.
- 50 11. In a machine for surfacing metal bodies, a base, means for causing relative movement of the base and the bodies to be surfaced, means on the base for supporting a torch-holder frame over the bodies, and mechanism for moving said frame transversely with respect to the base to accurately

position the frame over the bodies, said mechanism including manually operated means constructed and arranged to move the frame quickly and with little mechanical advantage, and manually actuated gearing having great mechanical advantage for moving said frame slowly to accomplish the final accurate positioning of said torch-holder frame.

12. Apparatus for removing metal from metal bodies comprising a plurality of torches with their tips disposed to direct touching oxidizing streams against the surface of the metal body, means for causing movement of the torches as a unit parallel to the surface of the metal body, means for shifting the torches as a unit to change the inclination at which the oxidizing streams are directed against the surface of the body, and other means for causing relative movement of the torches with respect to one another to dispose the tips along an arc for directing oxidizing streams against a transversely curved surface.

13. Torch supporting apparatus including in combination a frame, a plurality of torch holders connected to the frame and having a sliding movement on the frame, and means connecting the torch holders and operable to shift said holders and change the alignment of torches carried by the holders in the direction of the spacing of the torches from the work.

14. The combination of a plurality of torches, means holding the torches with their tips substantially equally spaced from a plane surface against which the torches direct streams of gas, and means operable to shift the torch holders and cause the torch tips to move into a curve to obtain substantially equal spacing of the tips from a transversely curved surface.

15. In a billet surfacing machine, a supporting frame, a plurality of torch holders connected with the frame and all except the end torch holders vertically movable on the frame, a stiff leaf spring extending through portions of the vertically movable torch holders, means restraining the ends of the leaf spring against vertical movement with respect to the frame, manually operated means for raising and lowering the center torch holder and bending the leaf spring into concave or convex arcs to shift the torch tips supported by the holders into convex and concave arcs for surfacing billets having such a transverse curvature, and means for holding said manually operated means in different positions to obtain various amounts of curvature of said spring.
